UNITED STATES PATENT OFFICE.

THOMAS A. WATSON, OF EVERETT, MASSACHUSETTS.

TELEPHONE-SIGNAL.

SPECIFICATION forming part of Letters Patent No. 240,208, dated April 12, 1881.

Application filed June 21, 1880. (No model.)

To all whom it may concern:

Be it known that I, THOMAS A. WATSON, of Everett, county of Middlesex, State of Massachusetts, have invented an Improvement in 5 Telephone-Signals, of which the following description, in connection with the accompanying drawings, is a specification.

My invention relates to telephone-signaling, and has for its object to enable an audible signal, sufficiently loud and of such distinctive character as to readily attract attention, to be given by the usual telephonic instrument, thereby obviating the necessity of bells or other expensive apparatus for signaling.

15 In one embodiment of my present invention the case of the usual microphone or battery transmitter, in which both electrodes are suspended by flexible supports, is provided with a whistle so placed as to be conveniently blown 20 by the operator, and adapted to impart a strong vibration to the diaphragm of the said transmitter, which will thus transmit the sound to the receiving-telephones in the usual manner. This kind of transmitter will give especially 25 good results, as the vibrations of the musical instrument will be conveyed to both electrodes, thereby greatly increasing the effect.

It will sometimes be preferable to set the diaphragm in vibration directly by the sonorous 30 column of air in the whistle, instead of transmitting the said vibrations in the usual manner through the air inclosed in the case of the microphone; and to accomplish this I preferably make use of a form of diaphragm or vibrator invented by G. L. Anders, in which two 35 plates are fastened together at their edges, which are free to vibrate, the middle of one of the said plates being fixed upon a support. As herein shown, the said plate would be supported at the end of the whistle which would 40 open into the space between the two plates, the column of air in its vibrations impinging directly upon the other plate, which acts on the electrodes of the microphone in the usual manner. When the transmitter is to be used only 45 for signaling, a whistle and diaphragm of this kind may be permanently connected with the frame-work supporting the electrodes; or when the transmitter is to be used for speaking, a 50 whistle open at its end may be inserted in the mouth-piece for signaling, and removed while the transmitter is used for talking.

It is well known that a musical note or continuous sound of uniform pitch transmitted to a receiving-telephone by electrical pulsations 55 in the usual manner will cause strong vibrations in the said telephone-diaphragm, emitting sounds that can be heard at a considerable distance, and this sound is especially loud when the note is in accord with the fundamental tone 60 of the diaphragm of the said telephone. The shrill tone of a common whistle will give a signal as well adapted to call attention as the ordinary bell, and is especially adapted for private lines, where an individual system is not required, and where it is desirable to have as little apparatus as possible.

Figure 1 is a front view of a microphone-transmitter provided with a whistle for signaling in accordance with my invention. Fig. 2 70 is a side view thereof; and Fig. 3, a sectional view, showing an arrangement to adapt the diaphragm to be directly vibrated by the sonorous column of air. Fig. 4 is a similar view, showing an ordinary form of diaphragm and mouth-piece, with a detachable whistle.

Figs. 1 and 2 illustrate the simplest embodiment of my invention.

A whistle, *a*, of proper sort to give a sharp shrill tone, and preferably made to harmonize 80 with the natural or fundamental tone of the receiving-telephone by which the signal is to be sounded, is inserted in the case *b* of a microphone or carbon transmitter of any usual form in such position as not to interfere with the 85 apparatus in the said case. That portion of the whistle *a* containing the sonorous column of air—or, in other words, the sounding part thereof—is wholly within the case *b*, and the sound-waves are transmitted by the air in the 90 case to the diaphragm of the transmitter, upon which they act with great intensity, owing to the directness of such transmission.

The mouth-piece *c* of the whistle is extended outside the case to enable the operator to sound 95 it readily, and, if desired, a flexible tube, *d*, and mouth-piece *e* thereon may be used for greater convenience in blowing the whistle.

In Fig. 3 the whistle *a* is shown in section attached to the frame-work *f* supporting the 100 diaphragm and electrodes of a microphone of common construction. The diaphragm shown is not of my invention, and is of peculiar construction, especially adapted to be vibrated by

the column of air of a whistle or other musical instrument. It consists of two plates, *m n*, connected together at their edges, an annular ring or washer, *o*, being inserted between them, and 5 the said edges being free to vibrate. The plate *m* is provided with a central opening, at the edges of which it is connected with a tube, *p*, forming a continuation of the whistle *a*. The column of air in the whistle *a* and tube *p* ex-
10 tends through the opening in the plate *m*, and in vibrating impinges strongly upon the plate *n*, setting it in vibration in unison with the said column of air. The plate *n*, in its vibration, acts in the usual manner on the electrodes, 15 causing a series of electric impulses to be transmitted, which, in turn, vibrate the diaphragm of the receiving-telephone in unison with the column of air in the whistle *a* in the usual manner, causing the said telephone to give out a
20 loud sound, sufficient to attract attention, for signaling purposes.
If desired, the whistle *a*, Fig. 3, can be removed and the transmitter used for talking.
A whistle or similar instrument may be 25 placed, as shown in Fig. 3, in the sound-passage leading to a diaphragm of common construction, and a whistle with an open end, as shown in Fig. 3, may be used with a transmitting-instrument of any kind, the said whistle
30 being fitted to the mouth-piece of the said transmitting-instrument, so that when inserted

therein the column of air in the said whistle acts directly on the diaphragm.

The whistle may have its end fitted to the mouth-piece of the telephone surrounded with 35 suitable material, such as cork or soft rubber, to enable it to be inserted tightly when desired to signal, and then be removed after the manner of a stopper; and the whistle may be connected with the telephone by a string or 40 chain, to insure that it will always be at hand when wanted. This arrangement is shown in Fig. 4, the letters indicating the same parts as on other figures.

I claim—

1. A battery-transmitter having both electrodes suspended by flexible supports and provided with an inclosing-case and whistle or musical instrument connected with said case. 50
2. A diaphragm composed of two plates connected together at the edges so as to leave a space between, in combination with a tube connected with a musical instrument and opening into said space.

In testimony whereof I have signed my name 55 to this specification in the presence of two subscribing witnesses.

THOMAS A. WATSON.
